COMBINED CANISTER AND COVER

John W. Ebstein, Roslyn Heights, N.Y., assignor, by
mesne assignments, to Federal Enameling & Stamping
Co., Pittsburgh, Pa., a corporation of Michigan

Filed Feb. 10, 1960, Ser. No. 59,345

Term of patent 14 years

(Cl. D44—6)

FIGURE 1 is a side elevational view of a combined canister and cover showing my new design, the opposite side being identical;

FIGURE 2 is an end elevational view thereof, the opposite end being identical;

FIGURE 3 is a top plan view;

FIGURE 4 is a bottom plan view; and

FIGURE 5 is a sectional view of the cover taken on line 5—5 of FIGURE 3.

I claim:

The ornamental design for a combined canister and cover, as shown and described.
